US00D774095S

(12) United States Design Patent (10) Patent No.: US D774,095 S
(45) Date of Patent: * Dec. 13, 2016

(54) DISPLAY SCREEN OR PORTION THEREOF
WITH ICON

(71) Applicant: Samsung Electronics Co., Ltd.,
Suwon-si (KR)

(72) Inventors: Seungwhan Kim, Seongnam-si (KR);
Jiny Kwon, Seongnam-si (KR);
Yukyoung Lee, Seoul (KR)

(73) Assignee: Samsung Electronics Co., Ltd.,
Suwon-si (KR)

() Term: 15 Years

(21) Appl. No.: 29/544,958

(22) Filed: Nov. 9, 2015

(30) Foreign Application Priority Data

May 27, 2015 (KR) 30-2015-0026672

(51) LOC (10) Cl. 14-04

(52) U.S. Cl.

USPC D14/493

CLAIM

We claim the ornamental design for a display screen or portion thereof with icon, as shown and described.

DESCRIPTION

The sole FIGURE is a front view for a display screen or portion thereof with icon showing our new design.

The dot-dash broken line showing of a display screen in the drawing FIGURE forms no part of the claimed design.

1 Claim, 1 Drawing Sheet
